UNITED STATES PATENT OFFICE

AUGUSTUS K. SWORTZEL, OF AKRON, OHIO

BRAIDING CARRIER

Application filed December 14, 1925. Serial No. 75,204.

This invention relates to new and novel improvements in braiding carriers and other devices in which a rotatably mounted feed spool is employed.

5 Objects of the invention, broadly stated, are to provide a spool carriage of simple, durable construction, which may be manufactured at a low cost and which in use will provide efficient means for holding a spool 10 whereby a supply of wire or other flexible material wound thereon may be drawn forwardly at an even tension.

A particular object is to provide a spool carriage having incorporated therein new 15 and improved braking means which will operate automatically to restrain a free unwinding movement of the spool and which may be quickly and conveniently adjusted to exert a predetermined axially directed pressure on said spool and further to provide 20 spring controlled means operated by the pull of the wire or other material as it is unwound from the spools and fed to the work.

25 An additional object is to provide a spool carriage having new and improved tension means which will operate accurately and uniformly during a rapid shifting movement of the carriage.

30 A further object is to provide a shiftable spool carriage having new and improved means for detachably securing a spool thereto whereby a spool may be quickly and conveniently removed or replaced when 35 desired.

A still further object is to provide a spool carriage of the type above indicated which is composed of separable parts detachably secured in assembled relation whereby a defective or broken part may be quickly and 40 conveniently removed and replaced.

The above objects are accomplished and other obvious advantages obtained by the novel construction, combination and arrangement of parts hereinafter described and illustrated in the accompanying drawing wherein I have shown one form of the invention, it being understood that the invention may be applied in various ways to 45 devices of the character herein described

and that changes and modifications may be made or resort had to substitutions which come within the spirit of the invention as set forth in the appended claims.

In the drawings which form a part 55 hereof like characters of reference are employed to denote like parts as the same may appear in any of the several views and in which:—

Figure 1 is a side elevational view of a 60 spool carriage constructed in accordance with this invention.

Figure 2 is a front, elevational view of 65 same showing the same with an empty spool, with the spool brakes in a locked position.

Figure 3 is a horizontal cross sectional view taken as indicated by the lines 3—3 of Figure 1.

Figure 4 is a front elevational view taken with the tensioning device in an upward 70 or operative position.

Figure 5 is a vertical, sectional view taken as indicated by the lines 5—5 of Figure 1.

Figure 6 is a horizontal, sectional view taken as indicated by the line 6—6 of Figure 75 1.

Proceeding now to a detailed description of the invention with reference to the particular adaptation thereof disclosed in the drawings, the numeral 5 is used to denote 80 a base plate which is provided on the lower side thereof with an elongated tongue 6 which is adapted to travel in a serpentine race-way of a braiding machine.

The numeral 7 denotes a bottom guide 85 plate which is held in parallel spaced relation to the plate 5 by means of the tongue 6 which is inserted therebetween. The numeral 8 denotes a lug which is secured to the lower face of the guide plate 7 for the purpose of engaging means for driving the carriage through the raceway.

The base plate 5 is provided on the upper side thereof with two spaced lugs 9. The numerals 10 and 11 are used to denote the 95 side members, each of which is secured to the base plate 5 by means of the bolt 12 or other suitable fastening means. The side members 10 and 11 extend upwardly in parallel spaced relation and are connected at 100

the upper end thereof by means of the top member 13, which is positioned between said top members and secured thereto by the bolts 14. The base member 5 is also provided at points adjacent the forward end 5 thereof with spaced lugs 15 and 16 which project upwardly from the upper face thereof, each of said lugs are provided on the upper face thereof with a suitable bore and one of the vertical rods 17, is mounted 10 in each of said bores. The rods 17 extend upwardly and are secured to the top member 13 by means of the nuts 18 and 19. The said member 10 is provided with an enlarged portion 10^a at a point intermediate its height and the side member 11 is likewise provided with an enlarged portion 11^a. The enlarged portions 10^a and 11^a are provided with axially aligned bores, the bore in 15 the portion 11^a being denoted by the reference character 11^b and the bore in the enlarged portion 10^a being denoted by the reference character 10^b. The bore 10^b is countersunk to provide a squared recess 10^c 20 for the squared head of the bolt 20 which is positioned through the bores 10^b and 11^b to support the spool 21 which is rotatably mounted thereon. The recess 10^c is of sufficient depth to accommodate the head 20^a 25 of the bolt 20 whereby the head 20^a of the bolt 20 will be flush with the outer face of the same member 10. The numeral 22 denotes a swinging member which is pivoted to the side member 10 as at 23, whereby it 30 may be swung over the head 20^a of the bolt 20 to retain said bolt in an operative position. It will thus be seen that the bolt 20 will be securely held in position without the aid of cotter pins, nuts or other fastening 35 means and that the spool 21 may be quickly 40 removed and replaced. The numeral 23^a denotes a spring which is secured to the swinging member 22 and to a lug 10^e to normally retain the swinging member from 45 the head of the bolt 20.

By reference to the drawings, it will be noted that the main portion of the side members 10 and 11 are vertical and that the upper ends of said side portions are inclined 50 forwardly whereby the top member 13 is positioned above the forward portion of the base plate 5.

Each of the side members 10 and 11 is provided at points above and below the enlarged portion 10^a and 11^a with a pair of spaced forwardly projecting ears 24. The numeral 25 denotes an arcuate braking member having each end positioned between the forwardly projecting ears 24 and hingedly 55 connected thereto by means of the bolt or pin 60 26 which is positioned through a bore extending through said ears 24 and through the ends of the arcuate member 25. The arcuate member 25 is provided adjacent the 65 upper end thereof with a forwardly project-

ing arm 27. The inner face of the arcuate member 25 is provided with a brake lining 28 which bears against the axial surface of the spool flange 21^a. A brake member 25 is thus hinged to each of the side members 10 and 11 70 for movement on a vertical axis whereby a movement of the arms 27 toward each other will bear against spool flanges 21^a and cause a braking action which will retard the free movement of the spool 21.

The numeral 29 denotes a spring having one end secured to one of the arms 27 and the other end adjustably secured to the other arm 27, whereby the arms 27 are normally held in an inward or braking position. While the spring 29 is preferably positioned at a point inwardly from the rods 17, it is understood that it may be positioned as desired and that other means may be employed to yieldably hold the braking members in an inward position. Each of the arms 27 are provided adjacent the forward end thereof with openings or bores 30 in which is mounted a headed rod 31. The rod 31 is 80 preferably secured to one of the side members 27 with the other side member slidably mounted thereon and is intended to prevent the arms 27 from swinging outwardly should the spring 29 become broken or otherwise 85 detached.

The numeral 32 is used to denote a member which is slidably mounted on the rod 17. The member 32 is provided with suitable bores 33 in which said rods are received. The lower portion of the member 32 is provided at the lower end thereof and on each lateral side thereof with an outwardly projecting lug 34 for the purpose of engaging the stop mechanism (not shown) of a braiding machine. The member 32 is provided with a centrally positioned opening 35 which extends therein from the upper edge thereof and in which is rotatably mounted the sheave 36. The member 32 is provided at the upper end thereof and on each lateral side thereof with a laterally presented wedge portion 32^a. The lateral faces of the wedge portions 32^a converge upwardly whereby an upward movement of the member 32 will cause the said faces to engage the arms 27 and move the said arms laterally apart. The member 32 is normally held in a downward position by means of the springs 37 which are mounted on the rods 17 and compressed against the upper faces of the wedge portions 32^a. The top member 13 is provided with an eye member 38 which is provided with a vertical bore and is positioned in operative alignment 100 with the sheave 36.

In use, the spool 21 is filled with wire or other flexible material. The member 22 is swung away from the recess 10^c. The bolt 20 is removed and the spool 21 is placed in position. The bolt 20 is then placed through 105 110 115 120 125 130

the openings 10^b and 11^b and through axial hole in the spool and the member 22 released to hold it in position. One end of the wire is placed under and in operative contact with the sheave 36 and is extended upwardly through the opening in the eye 38. As the 5 spring 29 operates to hold the brake members 25 against each flange 21^a of the spool 21, the spool 21 will be held against rotary movement and a pull exerted on the wire 39 will raise the member 32 until the converging lateral edges of the wedge members 32^a engage the arms 27. A further pull 10 on the wire 39 will cause the members 32^a to wedge the arms 27 laterally apart and will release the pressure of the brake members 25 on the flanges 21^a of the spool 21. As soon as this pressure is relieved, the spool 15 will rotate more freely, thus relieving the pull on the wire 39 and permitting a downward movement on the member 32 which will again cause an inward movement of the arms 27 and cause the members 25 to exert a braking action on the spool 21.

25 It will thus be seen that in operation, the wire 39 will be subject to an even tension regardless of the shifting movement of the spool carriage. This tension can be regulated by operating the screw 40 to regulate 30 the tension of the spring 29.

Having thus illustrated my invention and described the same in detail, what I claim as new and desire to secure by Letters Patent is:—

35 1. In a carrier for braiding machines, a frame, means to rotatably mount a spool thereon, a brake adapted to frictionally engage the axial face of said spool, yieldable means normally holding said brake in an operative position, brake releasing means 40 slidably mounted on said frame, a spring normally holding said releasing means in an inoperative position, said releasing means arranged to receive a flexible member wound 45 on said spool whereby the flexible member when subjected to a certain pull will overcome said spring and release said brake.

50 2. In a carrier for braiding machines, a frame including a base member and two side members, means to detachably and rotatably mount a spool between said side members, a brake member hingedly connected to each side member for swinging movement to and from the axial end of a spool mounted 55 on said frame, a spring connecting said brake members and normally holding the same in forced engagement with the end of the spool, a wedge-member slidably mounted on said frame, said wedge-member adapted 60 to be moved between said side members to swing the same laterally apart and release the pressure on said spool, a spring normally holding said wedge member in an inoperative position, means associated with 65 said wedge-member to engage a flexible

member wound on said spool and extending therefrom, said means arranged to overcome the action of said spring and move said wedge member into operative relation between said brake members when the flexible 70 member is subjected to a certain pull.

3. A spool carrier comprising a frame including a base member, two side members and a top member, means to detachably and rotatably mount a spool between said side members, an arcuate brake member hingedly connected to each side member for swinging movement to and from the axial end of a spool mounted on said frame, an adjustable 75 spring connecting said arcuate members and normally holding the same in forced frictional contact with the axial end of said spool; a wedge member slidably mounted on said frame and movable into an operative position between said arcuate members to swing the same laterally apart and relieve the pressure on said spool; a sheave mounted on said wedge member, an eye on said top member, a spring normally holding said wedge member in a downward position, said sheave adapted to receive a flexible member 80 from a spool mounted on said frame, said eye adapted to receive said flexible member extending from said spool around said sheave whereby a pull exerted on said flexible member will compress said second mentioned spring and raise said wedge member and move the same into an operative relation 85 between said arcuate members.

4. In a spool carrier, a frame including 90 a base member and two side members, means to detachably and rotatably mount a spool between said side members, a brake member hingedly connected to each side member for swinging movement to and from the axial end of a spool mounted on said frame, a spring connecting said brake members and normally holding the same in forced engagement with the end of the spool, a member 95 slidably mounted on said frame, said member adapted to be moved between said side members to swing the same laterally apart, a spring normally holding said member in an inoperative position, said member adapted to receive a flexible member wound 100 on said spool whereby said member will be moved into an operative position by a pull 105 on said flexible member.

In testimony whereof I have hereunto set 110 my hand.

AUGUSTUS K. SWORTZEL.
